(57) **CLAIM**

The ornamental design for television apparatus, as shown and described.

DESCRIPTION

FIG. 1 is a front perspective view of a television apparatus in accordance with my invention thereof;

FIG. 2 is a back perspective view thereof;

FIG. 3 is a front view thereof;

FIG. 4 is a left side view thereof;

FIG. 5 is a right side view thereof;

FIG. 6 is a back view thereof;

FIG. 7 is a top view thereof; and,

FIG. 8 is a bottom view thereof.
